UNITED STATES PATENT OFFICE

MARTIN C. BRIGHT, OF INDIANAPOLIS, INDIANA

AUTOMATIC GRAVITY CUT-OFF-CONTROLLING APPARATUS

Application filed August 22, 1925. Serial No. 51,790.

This invention relates to means primarily designed for preventing injury to persons and damage to machinery which may result from accidents when motor-propelled vehicles are overturned and in some cases causing conflagration, the invention having reference more particularly to means adapted to automatically operate upon overturning of a motor-vehicle to switch off or break the electrical sparking circuit of an internal combustion engine, or to electrically control a valve for stopping the flow of gasoline or fuel for the motor.

An object of the invention is to provide improved gravity-controlled apparatus for automatically controlling the cut-off of electrical or other energy required for operation of a motor or engine, to guard drivers or occupants of motor-vehicles against injury by fire which may result from wreckage involving the overturning of the motor-vehicle.

Another object is to provide an improved gravity controlling apparatus which shall be of such construction as to permit automatic breaking of an electrical conducting circuit and also manual control of the circuit, and yet be of simple and inexpensive construction as an inducement to general adoption.

A further object is to provide an electrical switching apparatus of such construction for motor-vehicles as to be adapted to operate by the force of gravity, and to automatically cause breaking of an electrical sparking circuit when the motor-vehicle is turned over in either one of a plurality of directions sufficiently in an accident likely to endanger the occupants thereof.

A still further object is to provide an automatic circuit-breaking apparatus which shall be of such construction as to be adapted to be applied in connection with various existing sparking circuit controls.

With the above-mentioned and other objects in view, the invention consists in novel means whereby an electrical conducting circuit shall automatically be broken immediately when an accident to a motor-vehicle occurs which in many cases may operate to hold the occupants of a motor-vehicle in or beneath

the resulting wreckage; and the invention consists also further in the parts and combinations and arrangements of parts as herein-after particularly described and further defined in the accompanying claims.

55

Referring to the accompanying drawing,— Figure 1 is a central section of one specific form of the apparatus in normal position with the weight element thereof held in relatively shifted position; Fig. 2 is an inner face view of one of the parts of the apparatus base and parts in section on the plane of the line II—II in Fig. 1; Fig. 3 is a fragmentary face view of the remaining part of the base and parts in section approximately on the line III—III in Fig. 1; Fig. 4 is a fragmentary section approximately on the line IV—IV in Fig. 1; Fig. 5 is a fragmentary reproduction of Fig. 2 with parts in relatively different positions; Fig. 6 is a fragmentary view similar to a portion of Fig. 3 with parts in relatively different positions; Fig. 7 is a fragmentary front view of the apparatus; Fig. 8 is a rear elevation of the modified form of the apparatus; Fig. 9 is a section approximately on the line IX—IX in Fig. 8; Fig. 10 is a section on the line X—X in Fig. 8; Fig. 11 is a fragmentary reproduction of Fig. 8 showing parts thereof in relatively different positions; and Fig. 12 is a perspective view of one of the electrical switch parts used in connection with the modified structure.

80

85

Similar reference characters in the various figures of the drawings indicate corresponding elements or features of construction hereinafter referred to in detail.

In practically carrying out the objects of the invention various specific structures may be adopted and the relative arrangement of elements may be varied, in every case a shiftable weight element, operating in either one of opposite directions by the force of gravity to attain the object sought, being present in the apparatus; and, the electrical switch may be adapted to be mechanically opened under hand-control, or may be adapted to be mechanically closed under hand-control.

90

95

A preferred form of construction comprises a base which conveniently is composed of two

100

parts 1 and 2 fixed together and having curved cavities 3 and 4 respectively in their inner sides, the two cavities together constituting a semi-circular guide channel, the ends of the channel extending upwardly when the base is in normal position. The base is composed of suitable material to constitute an electrical insulator and may be adapted to support various devices on the motor-vehicle. The base being considered as being in normal position, the two parts have also recesses 5 and 6 extending downwardly from the lowermost portion of the guide channel, and they have also grooves 7 and 8 respectively extending from the bottom of the recesses and forming a socket bore. The parts of the base are rigidly secured together by means of bolts, 9, 10, 11, and preferably by a bolt 12 nearly in the central portion thereof. A heavy ball 13 is arranged in the guide channel to roll on the circumferential wall portion of the channel and normally rest at the lowermost portion thereof.

A stud or binding post 14 is tightly inserted in the lower portion of the base part 2 and extends slightly into the part 1 so as to form the bottom of the socket 8 and constitute an electrical conducting element. A coil spring 15 is arranged in the socket upon the stud and is expansible into the recesses 5 and 6, the spring being an electrical conductor. A contact or connector block 16 is guided for vertical movement in the recesses and is supported upon the top of the spring which forces the block upward from the bottom of the recess when the block is not weighted. The top of the block is concave to conform to the curvature of the guide channel and preferably has a slight depression 17 to receive the ball 13 and ordinarily retain the ball centrally on the block so that the weight of the ball shall force the block to the bottom of the recess or cavity in which it is guided. A circuit wire 18 is connected to the stud or post 14 at the outer side of the part 2 and may constitute a part of an electric ignition system circuit.

A cup-shaped guide box 19 is tightly inserted in the lower portion of the base part 1 so as to be below the recess 5 and it has a plug 20 secured in its lower open end, the plug having a binding post 21 thereon which is provided with a nut 22 whereby a circuit wire 23 is connected to the plug, the wire being adapted to have connection with the sparking circuit. A coil spring is seated upon the plug and is adapted to constitute an electrical conductor. A switch rod 25 is arranged for vertical movement in the guideway 26 in the part 1 and extends through the bottom of the box 19, the rod having a head 27 thereon arranged in the box and upon the spring 24 which yieldingly forces the rod upward so as to slightly project into the recess 5 or against the bottom of the block 16 when the

block is weighted, thus completing an electrical circuit between the wires 18 and 23, the circuit to be broken automatically by action of the spring 15 when the block 16 is relieved of the weight of the ball 13.

The sparking circuit may be broken at will by any suitable switch, for stopping a motor, and may be most conveniently broken by means of a conventional switch lever and means to withdraw the switch rod 25 from contact with the block 16; and to this end, a pivot bracket 28 is secured to the lower portion of the front of the base part 1, and a lever or finger 29 is pivoted at one end to the bracket and extends through a suitable opening in the part 1 and the box 7 and to the back of the head 27, whereby to retract the switch rod 25. A switch lever 30 is provided with a supporting spindle 31 that is rotatively supported in the base, preferably centrally thereof, the spindle having a head 31' to which the lever is integrally connected. The lever has a cam 32 fixed thereto that is adapted to engage the top of the lever 29 when the lever is swung to vertical position and forces the lever 29 downward to break the circuit.

In the event of the overturning of the base in either one of opposite directions to an extent that would cause the ball 13 to roll out of the depression 17 and to one end of the guide channel, as when a motor-vehicle is overturned, resulting in the breaking of the sparking circuit, the ball is automatically locked to prevent its return. In providing locking apparatus the front of the part 1 preferably has a recess 33 arranged horizontally from the ends of which slots 34 and 35 extend through the wall of the part 1 to the recess 3 which forms a portion of the ball channel, and the front of the part 1 has pivot ears 36 and 37 adjacent to the recess. A locking arm 38 is pivoted to the ears 36 and extends into the slot 34, a locking arm 39 being pivoted to the ears 37 and extending into the slot 35. The arms are divergent each relatively to the other and may be swung out so as to project into the channel recess 3 to stop return of the ball. The arm 38 has a relatively obtuse-angled trip finger 40 on its pivoted portion that is engaged by a coil spring 41 seated in the recess 33 to force the arm into operative position, and the arm 39 has a similar finger 42 on its pivoted portion that extends against the outside of the finger 40 and has a rounded outer face, the finger normally holding the arm 39 in operative position. The finger 42 is adapted to be engaged by the lever 30 when it is swung to vertical position for retracting the arms from the ball channel.

A modification of the apparatus having specifically different details comprise a base 43 which is composed of electrical insulating material, and in the upper portion thereof a switch rod 44 horizontally guided which ex-

tends through the base and through a guide plate 45 on the back of the base, the plate being an electrical conductor to which a circuit wire 18' is connected. The switch rod 5 has a collar 46 thereon and a coil spring 47 is arranged under compression between the collar and the plate 45, being in a channel 48 in the base which permits the spring to move the switch rod forward a suitable distance. 10 A bushing 49 is secured in the base below the switch rod and rotatively supports a spindle 50 having a head 50' to which a switch lever or handle 30' is rigidly connected so as to be operated in a manner similar to that of the conventional sparking circuit switch lever. 15 The spindle is retained in place by means of a screw 51 and washer whereby a circuit wire 23' is connected to the spindle so as to be in electrical connection with the bushing 49. 20 The head 50' has a finger 52 fixed thereto that is adapted to be moved sidewise into contact with the front end of the switch rod 44 to force the rod back against the pressure of the spring 47. A switch plate 53 is pivotally mounted at one end on the bushing 49 and has a contact portion 54 at its opposite end adapted to be moved into contact with the rear end of the rod 44, or to be swung away from the rod to break electrical connection. 25 The plate 53 has lugs 55 and 56 on opposite sides thereof that are suitably spaced apart for shifting the plate pivotally. Preferably a backing bar 57 is secured to the base 43 and has a portion located opposite to the rear end of the switch rod 44, to assist in resisting the pressure of the rod against the contact portion 54 so as to insure proper electrical connection between the plate and the rod. A pendulum rod 58 is pivotally supported between its ends on the bushing 49, preferably being metallic and having a non-conducting lower arm portion 58'. The upper portion of the pendulum rod is arranged between the lugs 55 and 56 and has a head 59 thereon 30 which is non-conducting if the rod 58 be metallic, the head being so arranged as to be carried to either one of the lugs by the pendulum rod. The lower end of the pendulum rod or arm has a heavy weight element 60 fixed thereto to normally maintain the pendulum rod in approximately perpendicular position. The space between the lugs 55 and 56 permits a limited amount of swinging movement of the pendulum arm without moving the contact portion 54 away from the switch rod during the usual operation of a motor-vehicle. 35

In order to lock the pendulum arm against return to normal position after the motor-vehicle has overturned and caused swinging of the pendulum arm sufficiently to break the circuit, a plurality of locks are provided, pivot ears 61 and 62 being supported on the back of the base 43 at a suitable distance from 40 the lower end of the base and spaced apart on opposite sides of the normal position of the pendulum arm, and two latch bars 63 and 64 are pivotally supported between their ends on the ears respectively, the ears extending horizontally behind the pendulum arm or rod. The latch bars have off-set latch portions that are normally held yieldingly on the plane of movement of the pendulum arm by means of coil springs 65 and 66 respectively that are seated in sockets in the base and preferably have caps 67 and 68 on their ends that bear against the latch bars. Coil springs 69 and 70 are arranged behind the latch bars adjacent to their inner ends and are seated in sockets 71 and 72 respectively which are movable in suitable sockets in the base and provided with push-rods 73 and 74 respectively to which a yoke 75 is secured, the face of the yoke being convexly curved or cam-shaped so as to be engaged and forced towards the base to move the sockets when the lever 30' is swung to vertical position. The springs 69 and 70 are slightly weaker than the springs 65 and 66 so as to assist in rocking the latch bars when their outer ends are moved by the pendulum arm as it swings against the off-set portions of the latch bars to become locked against return after passing the ends of the bars. When the latch bars are required to be rocked to release the pendulum arm the springs 69 and 70 will yield as the sockets 71 and 72 are forced towards the bars, permitting the sockets to engage the bars and forcibly rock them in opposition to the springs 65 and 66. 45

It will be obvious from the foregoing description that the base of the controlling apparatus is to be mounted on the instrument board of a motor-vehicle so that the switch lever may be conveniently reached by an operator, the front of the base being approximately vertical on a transverse plane permitting the weight element to move transversely relatively to the motor-vehicle. 50

In practical use of the form of apparatus shown in Figures 1 to 7 inclusive, the weight ball is supported upon the connecting block 16 which is held down and forms electrical circuit between the spring 15 and the switch rod 25, maintaining electrical connection between the wires 18 and 23, the switch lever 30 being in inclined position as indicated by broken lines in Figures 3 and 7, to supply current in the ignition system. The circuit may be broken at will by swinging the lever 30 to vertical position which results in the cam 32 engaging the lever 29 which forces the rod 25 away from the block 16 as appearing in Figure 3 without disturbing the block 16 which would be held down by the ball as in Figures 5 and 6. The usual jolting due to operation of the motor-vehicle does not dislodge the ball but in case of a serious accident resulting in overturning of the motor-vehicle, in either one of opposite directions, the ball

13 inevitably rolls from the block 16 and permits the spring 15 to push the block upward away from the rod 25 as shown in Figures 1, 2 and 3, thus breaking the electrical circuit, 5 the ball rolling to one end of its guide channel and pressing back its latch bar which is spring-pressed out again and prevents return of the ball. The motor being stopped for lack of electrical current no injury or damage 10 can result which might be due to operation of the motor. When an accident is imminent the current may be switched off manually, but in most cases manual switching is impossible or neglected, when an automatic breaking of 15 the circuit must be relied upon to safeguard those who may be victims of the accident.

In the event that the motor-vehicle can be righted, the locked gravity ball prevents connection of the circuit; but the switch lever 20 may be first swung to vertical or "off" position which automatically causes release movement of the latch bar 38 or 39, as the case may be, permitting the ball to roll down and gravitate to its normal position upon the 25 block 16, thus holding the block down in normal position to be engaged by the rod 25 when released by operation of the lever 30 in case it be desired to operate the motor.

In practical use of the form of apparatus 30 shown in Figures 8 to 11 inclusive, which is suitable particularly for high-tension current, it will be apparent that in the ordinary operation of the automobile the connecting plate 53 is set behind the bar 57 or opposite to 35 the switch rod 44 which is spring-pressed back to break the circuit, the circuit being closed when the rod is forced by the finger 52 into contact with the contact portion 54. The pendulum may swing a limited extent, 40 as indicated by broken lines in Figure 8 without becoming latched or moving the connection plate 53, but in case of the motor-vehicle becoming overturned the pendulum rod is swung over sufficiently to cause movement of 45 the connecting plate 53 so as to become disconnected from the switch rod 44, the relative positions being indicated in Figure 11, the pendulum rod having passed its latch bar and being prevented from returning. Following 50 an overturning, in the event that the motor-vehicle is righted on a road the switch lever 30' is first moved to vertical position to carry the finger 52 away and release the switch rod 44, if need be, the lever operating 55 the latch bars 63 and 64 so as to release the pendulum rod which then swings sufficiently to move the connecting plate 53 and bring the contact portion 54 into normal position 60 opposite to the end of the retracted rod 44, after which the circuit may be normally established or be broken by manipulation of the lever 30'.

By reference to the foregoing description 65 other results of the operation of the appara-

tus will readily be understood without further detail description.

What is claimed as new is:

1. A cut-off controlling apparatus including a normally vertical base, a movable gravity-weight element, means co-operating with the base to support and guide the weight element for movement in either one of opposite directions on an arc, a switch lever pivoted on the base, an electrical switch supported by the base, means on the base enabling the lever to operate the switch, and means on the base enabling the weight element upon movement in either one of the opposite directions to operate the switch. 70

2. A cut-off controlling apparatus including a normally vertical base, a weight element, means co-operating with the base to movably guide the weight element in either one of opposite directions on an arc, a switch lever pivoted on the base, an electrical switch supported by the base, means on the base controlled by the lever to control the switch, means on the base controlled by the weight element to control the switch, and a plurality 85 means controlled by the lever supported on the base to lock the weight element against return movement. 90

3. A cut-off controlling apparatus including a normally vertical base having a guide 95 cavity therein, an electrical connector block vertically movable in the cavity and yieldingly supported therein, the block having an electrical terminal thereon, an electrical switch rod vertically movable in the base below the cavity and yieldingly supported 100 therein, a finger movably supported by the base and having operative connection with the switch rod, a lever pivotally supported on the base and adapted to engage the finger 105 for withdrawing the switch rod from the connector block, and a gravity-controlled device operating to normally hold the connector block down to the switch rod, the device being shiftable to release the block upon the overturning of the base. 110

4. An automatic gravity cut-off controlling apparatus comprising a base to be vertically supported, an electrical switch element movably guided by the base, a spring co-operating with the base to move the switch element in one direction, an electrical circuit connector guided by means of the base and shiftable to the switch element to complete the circuit, a manually-operated switch lever pivotally supported by the base and a device on the base controlled by the lever to engage and move the switch element in the opposite direction, a circuit wire having connection with the switch element, a circuit wire having connection with the circuit connector, a weight element movably guided by means of the base and operating by the force of gravity in connection with the connector to shift the latter to the switch element, the weight 125 130

element being free to move in one of different directions upon overturning of the base and adapted to control the breaking of the circuit by shifting of the connector from the switch element, and locking means mounted on the base automatically operating to engage and hold the weight element following its movement.

5. In an electrical cut-off controller, the combination of a base to be vertically supported, an electrical switch rod supported for longitudinal movement in the base and provided with a spring to move the rod in one direction, a lever pivotally mounted on the base, a device on the base to be actuated by the lever to move the switch rod in the opposite direction, an electrical connector shiftably supported by means of the base to be connected with the switch rod, a circuit wire having electrical connection with the switch rod, a circuit wire having electrical connection with the connector, and a gravity-controlled device movably guided in the base for controlling the connector to automatically disconnect the connector from the switch rod upon overturning of the base.

6. In an electrical cut-off controller, the combination of a normally vertical base having a curved guide channel therein, the ends 30 of the channel being higher than the main portion of the channel, the base having a recess at the lowermost portion of the channel and a vertical socket bore at the bottom of the recess, a conducting stud secured in the base and extending to the bottom of the socket bore, an electrical conducting connector block vertically guided in said recess, a conducting spring in said bore and seated on said stud and supporting said block above the bottom of said recess, a switch element supported in the base and normally projecting yielding into said recess, means to manually withdraw the switch element, and a weight ball movably guided in said channel and normally supported upon said block and holding the block down in the recess.

7. In an electrical cut-off controller, the combination of a normally vertical base having a guide cavity therein, a conducting electrical connector block vertically movable in the cavity, a conducting circuit spring yielding supporting the block in the cavity above the bottom thereof, an electrical switch rod vertically movable in the base below the cavity, a spring supported in the base and yielding pushing the switch rod partially into the cavity, a finger pivotally supported by the base and having operative connection with the switch rod, a lever pivotally supported on the base and having a cam thereon to be carried into contact with the finger for withdrawing the switch rod from the connector block, and a gravity-controlled device supported by the base and operating to normally hold the connector block down to the

switch rod, the device being shiftable to release the block upon the overturning of the base.

8. In an electrical cut-off controller, the combination of a normally vertical base having a curved transversely arranged guide channel therein, the ends of the channel being higher than the middle portion thereof, an electrical switch rod supported in the base below the channel, an electrical connector block movably guided in the base below the channel to be depressed to the switch rod, an electrical conducting spring supported in the base and yielding supporting the connector block above the switch rod, a weight ball movably arranged in the guide channel and normally gravitating onto the connector block and depressing the block to the switch rod, the ball automatically shifting to one end of the channel and releasing said block when the base is overturned, two latch bars movably supported by the base and spring-pressed to normally project into the guide channel behind the ball when at the end of the channel, and means to retract the latch bars simultaneously.

9. In an electrical cut-off controller, the combination of a normally vertical base having a curved transversely arranged guide channel therein, the two opposite ends of the channel being the higher portions thereof, an electrical switch element supported in the base below the channel, an electrical connector device yielding supported and guided in the base below the channel, a weight ball movably arranged in the guide channel and normally gravitating onto the connector device and depressing the device to the switch element, the ball automatically shifting to one of the two ends of the channel and releasing said connector device when the base is overturned, two latch bars movably supported by the base and spring-pressed to normally project into the guide channel behind the ball when at one end of the channel, one of the latch bars controlling the other, and a lever arm pivotally supported by the base to engage and control the controlling one of the latch bars.

In testimony whereof, I affix my signature on the 7th day of August, 1925.

MARTIN C. BRIGHT.
